UNITED STATES PATENT OFFICE

138,851

DESIGN FOR A HAT

G. Howard Hodge, New York, N. Y.

Application July 25, 1944, Serial No. 114,554

Term of patent 3½ years

(Cl. D3—13)

To all whom it may concern:

Be it known that, I, G. Howard Hodge, a citizen of the United States of America, residing in New York city, county of New York, and State of New York, have invented a new, original, and ornamental Design for a Hat, of which the following is a specification, reference being had to the accompanying drawing, forming part thereof.

Fig. 1 is a rear view of a hat showing my new design.

Fig. 2 is a front perspective view thereof.

I claim:

The ornamental design for a hat, substantially as shown.

G. HOWARD HODGE.
